DESIGN FOR AN ASHTRAY

José P. Sandejas, Manila, P. I.

Application September 19, 1939, Serial No. 87,290

Term of patent 7 years

To all whom it may concern:

Be it known that I, José P. Sandejas, a citizen of the Philippine Islands, residing at Manila, Philippine Islands, have invented a new, original, and ornamental Design for an Ashtray, of which the following is a specification, reference being had to the accompanying drawing forming part thereof.

In the drawing:

Fig. 1 is a perspective view of an ashtray showing my new design; and

Fig. 2 is a vertical sectional view of the same, taken on the line 2—2 of Fig. 1.

I claim:

The ornamental design for an ashtray, as shown.

JOSÉ P. SANDEJAS.
